UNITED STATES PATENT OFFICE

JOHN M. HOTHERSALL, OF BROOKLYN, NEW YORK, ASSIGNOR TO AMERICAN CAN COMPANY, OF NEW YORK, N. Y., A CORPORATION OF NEW JERSEY

WIRE-EDGED CONTAINER AND CLOSURE THEREFOR

Application filed December 10, 1925. Serial No. 74,436.

My invention relates to containers, preferably of the type having a curled or false wire edge at the mouth thereof, and to closures for such containers.

5 The principal object of my invention is to provide an improved closing member for attaching a loosely positioned cover to a can body, which may be applied by simple and inexpensive machinery and which, 10 though providing a tight and effective seal, may be easily and conveniently removed by hand to open the container and without bending or mutilating the can body.

Still another object of the invention is 15 the provision of a one-piece sealing or closing member which is constructed and arranged to be easily removed from the can body and replaced as a temporary closure after the can has once been opened.

20 The closing member of my invention preferably has a curled edge adapted to be forced into sealing engagement with the rolled edge of the can body in the attaching operation and an important feature of the construction

25 is that the curled edge is split at one or more places, which serves the double purpose of facilitating removal and providing flexibility as the gripping edge of the closure is contracted in the attaching operation, thereby 30 increasing the tension of said edge and tightly clamping the cover to the can body.

Other objects and advantages of the invention will be apparent as it is better understood from the following description, 35 which, taken in connection with the accompanying drawings, discloses preferred embodiments thereof.

Referring to the drawings,

Figure 1 is a perspective view of my improved cover;

Fig. 2 is a similar view of the can body,

Fig. 3 is a partial sectional view showing the rolled edge of the cover prior to being unrolled into sealing position;

45 Fig. 4 is a similar view showing the curled edge unrolled and in sealing position;

Fig. 5 is a partial sectional view of a modification of my invention showing the curled edge before being forced into sealing position 50 over the rolled edge of the can body, and

Fig. 6 is a corresponding view showing the curled edge forced into sealing position.

Referring now to the drawings in detail as illustrating one or more of the preferred means in which I have thus far contemplated applying the principles of my invention, the can body 1 being provided with a rolled edge or false wire 2 forming a hollow lip at the top thereof, the can body being formed with the usual side seam 3 and with a bottom end 4 applied thereto. The lower terminal part of this lip is preferably substantially horizontal and braced against the body to prevent the collapse of the hollow lip or false wire 2 when the cover is applied with considerable pressure.

The cover 5 is formed with a vertical wall or shoulder 6 adapted to be located within the body wall 7, and this vertical wall 6 extends into a circumferential flange 8 adapted to 70 rest upon the top of the false wire 3 and is returned upon itself, as at 9, a gasket or any suitable sealing medium 10 being provided if desired.

In accordance with my improved invention, this circumferential flange 8 of the cover is constructed and arranged to cooperate with the wire edge of the can body so that the cover can be forced into gripping and sealing contact with the can body and can 75 likewise be easily and quickly removed therefrom and thereafter reapplied as a temporary closure, all without mutilating the can body. To this end the flange 8, is formed with an outwardly and tightly curled edge 11, as shown in Fig. 3 of the drawings, and in addition the flange 8 is provided with one or more slits 12, preferably spaced equi-distant circumferentially about the periphery of the flange and extending from the free edge of 80 the flange to substantially near the end thereof, but not quite to the top, as indicated at 13, whereby to give the cover sufficient flexibility in applying and removing the cover.

In applying the cover to the can body, the 85 cover is placed in position and the tightly rolled edge 11 is partially unrolled and positively positioned beneath the curl of the body as indicated in Fig. 4 of the drawing.

Figs. 5 and 6 illustrate a modification of 100

the closure. In this form the curl 14 is formed on the inside of flange 15 of the cover 16 and is merely forced over into locking position with the false wire 17 of the can body as indicated fully in Fig. 6 of the drawings.

While I refer to the invention as being applied to a metal container with a rolled upper edge, it should be understood that the invention is equally well adapted to a container 10 made of glass or similar material having its upper edge formed into a projecting flange.

It is thought that the invention and many of its attendant advantages will be understood from the foregoing description, and it 15 will be apparent that various changes may be made in the form, construction and arrangement of the parts without departing from the spirit and scope of the invention or sacrificing all of its material advantages, the 20 form hereinbefore described being merely a preferred embodiment thereof.

I claim:

1. In combination, a container having a retaining portion at the top thereof, a cover 25 arrangeable upon said body and having a flange arrangeable over said retaining portion, said cover flange having a peripheral rolled edge adapted to be partially unrolled by pressure thereon to dispose it in sealing engagement with the retaining portion of the 30 body.

2. In combination, a container having a retaining portion at the top thereof, a cover arrangeable upon said body and having a 35 countersink disposed within the mouth of said retaining portion and a flange arrangeable over said retaining portion, said cover flange terminating in a rolled edge adapted to be partially unrolled by pressure thereon 40 to dispose it in sealing engagement with said retaining portion of the body.

3. In combination, a container having a rolled flange at the top thereof, a cover arrangeable upon said body and having a 45 countersink disposable within the mouth of said rolled flange, said cover having an inverted substantially U-shaped flange arrangeable on said rolled flange and provided with a peripheral rolled edge split at spaced intervals, said rolled edge being adapted to be partially unrolled to cause it to move inwardly beneath the rolled flange of the body to detachably hold the cover in place.

4. A container closure having in combination 55 a body having its mouth formed with an outwardly, downwardly and inwardly rolled hollow lip the lower terminal part of which is substantially horizontal, and a cover having a shoulder engaging within the inner wall 60 of said hollow lip and having a circumferential flange which extends outward over the top of said lip and downward on the outer side thereof, the edge of said flange having a curl which is forced inward under said lip 65 and near to the lower part of said shoulder.

5. A container closure having in combination a body having its mouth formed with an outwardly, downwardly and inwardly rolled hollow lip the lower terminal part of which is substantially horizontal and is braced 70 against the body to prevent collapse of said lip when the cover is applied with pressure, and a cover having a shoulder engaging within the inner wall of said hollow lip and having a circumferential flange which extends outward over the top of said lip and downward on the outer side thereof, the edge of said flange having a curl which is forced 75 inward under said lip and towards said shoulder.
